DISPENSING DEVICE

Reinor O. Lilja, Raymond C. Stephan, and Walter F. Ohme, Minneapolis, Minn.; said Lilja assignor to North Star Specialty & Manufacturing Company, Minneapolis, Minn., a corporation of Minnesota

Application March 18, 1940, Serial No. 324,480

11 Claims.

(Cl. 225—27)

Our invention relates to dispensing devices and particularly to devices for dispensing liquids such as milk and milk products and similar substances.

An object of the invention resides in providing a dispensing device in which the liquid is agitated as the same is being dispensed.

Another object of the invention resides in providing a device in which the liquid is aerated during the flow thereof.

An object of the invention resides in providing a valve for controlling the flow of liquid from the container and in incorporating in the valve an agitator.

Another object of the invention resides in utilizing an electric motor for operating the agitator and in mounting said motor on the valve.

A feature of the invention resides in constructing the dispensing device with a valve body having a vertically extending bore therein preferably conical and flaring upwardly.

An object of the invention resides in providing a spout at the lowermost portion of the bore providing a discharge outlet for the liquid dispensed.

Another object of the invention resides in providing an inlet at the uppermost portion of the valve body.

A still further object of the invention resides in providing a cup-shaped valve member disposed within the bore of the valve body and having a chamber therein.

A feature of the invention resides in constructing the valve member with passageways for bringing the inlet into communication with the chamber at the lowermost portion thereof and for bringing the uppermost portion of the chamber into communication with the discharge outlet.

Another object of the invention resides in arranging said passageways in such a manner that rotation of the valve member will close the inlet and connect the lowermost portion of the chamber in the valve member with the discharge outlet so as to permit of draining the contents of the chamber therefrom.

A feature of the invention resides in disposing the agitator within said chamber at the lowest portion thereof.

An object of the invention resides in providing the motor attached to said valve member with a shaft extending into said chamber and on which the agitator is mounted.

Another object of the invention resides in constructing the valve member with a neck extend-

ing upwardly therefrom and providing a sleeve encircling said neck and to which the motor is attached.

A feature of the invention resides in detachably securing the motor to the sleeve and the sleeve to the neck and in utilizing the weight of the motor for holding the valve member seated within the bore of the valve body.

An object of the invention resides in attaching a handle to the sleeve and in providing a key between the sleeve and valve member, whereby rotation of the valve member can be procured by swinging of the handle.

Other objects of the invention reside in the novel combination and arrangement of parts and in the details of construction hereinafter illustrated and/or described.

In the drawing:

Fig. 1 is an elevational view of a dispensing device for liquids illustrating an embodiment of my invention.

Fig. 2 is an elevational sectional view of a portion of the structure shown in Fig. 1, viewed from a position at right angles to that from which Fig. 1 is taken and drawn to a greater scale.

Fig. 3 is a plan sectional view taken substantially on line 3—3 of Fig. 2.

Fig. 4 is a plan sectional view taken on line 4—4 of Fig. 2.

Fig. 5 is a plan sectional view taken on line 5—5 of Fig. 2.

Fig. 6 is a fragmentary view similar to Fig. 2 showing the parts in altered position.

Fig. 7 is a plan sectional view taken on line 7—7 of Fig. 6.

Our improved dispensing device is indicated in its entirety by the reference character A and includes a valve structure B. The valve structure B comprises a valve body 10 having a valve member 11 therein formed with a chamber 12 in the same. In this chamber is provided one or more agitators 13 carried by an electric motor 14 which is mounted on the valve member 11. By means of this construction the liquid passing through the valve A is agitated by the agitators 13 during the flow thereof through the valve. These various parts will now be described in detail.

The valve body 10 is conical in form and is formed with a frusto-conical bore 16 which is situated vertically and which is open at the top and bottom. To the lowermost portion of the valve body 10 is attached a spout 17 which is also conical in form, being constructed with a flaring wall 18 and with a tapered wall 19 following along

the outer surface 21 of the body 10. The wall 19 is received within a recess 22 in the lowermost portion of the valve body 10, and is held in place by means of two pins 23 attached to said valve body and disposed in the recess 22, which pins are adapted to enter bayonet slots 24 in the wall 19 of the spout 17. The spout 17 has a chamber 43 in the same which communicates with a discharge outlet 25 from which the liquid dispensed is discharged. At the uppermost portion of the valve body 10 is provided a boss 26 which has a passageway 27 therein. This boss is threaded at 28 to screw on to a pipe or fitting 29 which may be connected to a reservoir or other supply of the liquid to be dispensed. The passageway 27 terminates in a port 30 extending through the wall of the body 10 formed by the bore 16 and which forms an inlet for the valve structure B.

Within the bore 16 of the body 10 is disposed the valve member 11 which is cup-shaped in form and which has a frusto-conical surface 31 adapted to closely fit along the surface of the bore 16. This valve member has a relatively thick bottom 32 and a fairly thick circumferential wall 33 which form the chamber 12 within the same. Said valve member is open at the top and is constructed with a neck 34 projecting upwardly therefrom, and which lies inwardly of the surface 31 of the wall 33 to form a shoulder 35 therebetween. In the bottom 32 of the valve member 11 is drilled a hole 36 which provides a port 37 communicating with the chamber 12. A radially extending hole 38 communicates with the hole 36 and extends through the surface 31 of the said valve member. This hole communicates with a groove 39 extending along the surface 31, which groove in one position of the valve member 11, is adapted to communicate with the port 30 of the passageway 27. It will be readily comprehended that, when the valve member 11 is in the position shown in Fig. 2, the liquid to be dispensed may flow through the passageway 27 along the groove 39 and through the holes 38 and 36 and into the chamber 12. The valve member 11 is further constructed with ports or holes 41 in the circumferential wall 33 thereof, which are situated at about the same elevation as the port 30. These holes communicate with grooves 43, which are formed in the wall 33 and extend through the surface 31 of the valve member 11. These grooves extend through the bottom 32 and bring the interior of the chamber 12 at a locality considerably above the bottom thereof in communication with the chamber 43 formed within the spout 17. When the parts are arranged, as shown in Fig. 2, the liquid entering the chamber 12 rises to the elevation of the ports 41 and is discharged outwardly therefrom and along the grooves 42 into the chamber 43 and nozzle 17. The said liquid then leaves the nozzle through the discharge outlet 25 thereof. It will thus be readily comprehended that the various parts of the valve body and valve member form a conduit through which the liquid flows from the receptacle to the discharge spout 17, and that the flow of liquid is cut off at the port 30. It is also to be noted that the chamber 12 constitutes an enlargement of a portion of said conduit.

Encircling the neck 34 of the valve member 11 is a sleeve 44, the lower edge of which rests upon the shoulder 35 of said valve member. This sleeve has a keyway 45 therein which is adapted to engage a key 46 secured to the valve member 11. The key 46 is attached to said valve

member by means of a pin 47 and may be soldered or brazed to the said valve member. The key 46 also forms a limiting device for limiting the rotation of the valve member 11. For this purpose two stops 48 and 49 are employed which consist of pins set into the upper portion of the valve body 10. These pins are so situated that the valve member 11, when in its open position, as shown in Fig. 2, engages the pin 48 and when 10 in its closed position, as shown in Fig. 6, engages the pin or stop 49.

The sleeve 44 has attached to it a mounting 51 which is secured thereto by means of rivets 52. This mounting is formed with a threaded boss 53 adapted to receive the shank 54 of a handle 55. By means of this construction the sleeve 44 may be rotated. Due to the key 46 and the keyway 45, rotation of the sleeve 44 causes rotation of the valve member 11.

20 The motor 14 may be of the conventional type, being constructed with a core structure 56, which is clamped between end bells 57 and 58. These end bells journal the armature shaft 57 of the motor to which the agitators 13 are attached.

25 The shaft 57 is of such length that the agitators 13 become positioned beneath the ports 31 and above the bottom of the valve member 11 within the chamber 12 therein. These agitators, when the motor is operated, introduce air bubbles into the liquid passing through the chamber 12 which give the liquid a foamy form when leaving the ports 41. To prevent rotation of the liquid and render the agitators 13 more efficient, two swirl breakers 58' are employed which extend along the inner surface of the valve member and are disposed within the chamber 12.

30 The motor 57 is attached to the sleeve 44 by means of a flanged mounting 59. This mounting has a tubular portion 61 which extends into the uppermost portion of the sleeve and a flange 62 attached to the end bell 58. The tubular portion 61 has secured to it a stud 63 which is provided with a nut 64. Nut 64 has a conical end 65 adapted to engage in a conical socket 66 in the upper portion of the sleeve 44. A slot 67 in the said upper portion of the sleeve receives the stud 63 and permits of inserting the tubular portion 61 into the said sleeve. When the nut 64 is tightened the parts are held in locked position.

35 The valve body 10 of valve B is constructed upon the inner surface of the bore 16 thereof with a groove 68, best shown in Figs. 6 and 7, which is disposed in circumferentially spaced relation to the port 29 and which is situated at the lowermost portion of said valve body. This groove is adapted to communicate with the hole 38 in the valve member 11 and also with the chamber 43 within the spout 17, when the valve member 11 is in closed position, as shown in Fig. 7. In such position the port 30 is covered up and the hole 38 brought into communication with the groove 68. This permits the liquid within the chamber 12 to drain out of the same and to be discharged through the spout 17 along with the liquid normally passing through the ports 41. In this way the device is completely emptied of liquid.

40 The operation of the invention is as follows: Normally the valve member 11 is in closed position as shown in Figs. 6 and 7, and no liquid passes through the same. When the valve member is rotated by means of handle 55 to the position shown in Fig. 2, liquid flows through the passageway 27, the port 30, groove 39 and holes

38 and 36, and port 37 into the chamber 12. Upon energization of the motor 14, the agitators 13 are set into action which beats up the liquid within the chamber 12 and aerates the same. The liquid so acted upon passes outwardly through the ports 41 and along the grooves 42 into the chamber 43 of spout 17 from which the liquid is discharged through the discharge outlet 25. When the valve is closed the residue of the liquid within chamber 12 drains out through the holes 36 and 38 and the grooves 68 into chamber 43 of spout 17 from which the same is discharged out of the spout together with the liquid entering said chamber through ports 41. When it becomes desirable to clean the device, the spout 17 may be removed by rotating the same and disengaging the pins 23 from the bayonet slots 24. The valve member 11 may next be raised out of the bore 16 of the valve body 10 and the sleeve 44 disconnected therefrom and motor 14 removed from the sleeve. All of the parts which come in contact with the liquid are thus readily accessible and may be washed and cleaned.

The advantages of our invention are manifest. Our improved dispenser may be used for dispensing and aerating, stirring or mixing milk or milk products such as malted milk or may be used with any viscous liquid requiring stirring, mixing or aeration. The device is extremely simple and practical in construction. With our invention the liquid to be dispensed is agitated as it passes through the valve. Due to the construction and arrangement of parts our dispensing device is extremely sanitary and may readily be taken apart for the purpose of cleaning. By constructing the valve member with grooves, upon the exterior surface thereof, the same is readily cleaned and all of the liquid adhering to the same may be readily removed. Our invention may be constructed at a nominal cost and may be used with any container or receptacle in which a liquid to be dispensed is contained.

Changes in the specific form of our invention, as herein disclosed, may be made within the scope of what is claimed without departing from the spirit of our invention.

Having described our invention, what we claim as new and desire to protect by Letters Patent is:

1. In a dispensing device for liquids, a valve body having a vertical bore therein and provided with a discharge outlet and an inlet, a cup-shaped valve member disposed within said bore and formed with a chamber within the same, said chamber being in communication with said outlet and inlet, said valve member upon rotation to one of its positions closing said inlet, a support issuing upwardly from said valve member, a motor carried by said support and disposed exteriorly of said valve body, and an agitator operated by said motor and disposed within said chamber.

2. In a dispensing device for liquids, a valve body having a vertical bore therein and provided with a discharge outlet and inlet, a cup-shaped valve member disposed within said bore and formed with a chamber within the same, open at the top, said chamber being in communication with said outlet and inlet, said valve member upon rotation to one of its positions closing said inlet, a tubular neck extending upwardly from said valve member, a motor carried by said neck, said motor having a shaft extending through said neck and into said chamber through the open end thereof, and an agitator on said shaft disposed within said chamber.

3. In a dispensing device for liquids, a valve body having a vertical conical bore flaring upwardly and provided with a discharge outlet and an inlet, a cup-shaped conical valve member insertable into said bore from above, said valve member having a chamber therein adapted to communicate with said inlet and said outlet, said valve member upon rotation to one of its positions closing said inlet, a motor carried by said valve member, the weight of said motor holding said valve member seated in said bore, and an agitator operated by said motor and disposed within said chamber.

4. In a dispensing device for liquids, a valve body having a vertical bore and provided with a discharge outlet and an inlet, a cup-shaped valve member disposed within said bore, and formed with a chamber within the same communicating with said inlet and outlet, said valve member upon rotation to one of its positions closing said inlet, a sleeve extending upwardly from said valve member, an electric motor, means on said electric motor adapted to engage said sleeve for supporting the motor on the valve member, means for detachably securing said means to said sleeve, a shaft operated by said motor and extending through said sleeve and into said chamber, and an agitator carried by said shaft and disposed in said chamber.

5. In a dispensing device for liquids, a valve body having a vertical bore and provided with a discharge outlet and an inlet, a cup-shaped valve member disposed within said bore, and formed with a chamber within the same communicating with said inlet and outlet, said valve member upon rotation to one of its positions closing said inlet, a sleeve extending upwardly from said valve member, a handle secured to said sleeve for rotating the same and said valve member, a shaft extending through said sleeve and into said chamber, an agitator carried by said shaft and disposed within said chamber, and means for operating said shaft.

6. In a dispensing device for liquids, a valve body having a vertical bore and provided with a discharge outlet and an inlet, a cup-shaped valve member disposed within said bore, and formed with a chamber within the same communicating with said inlet and outlet, said valve member upon rotation to one of its positions closing said inlet, a neck extending upwardly from said valve, a sleeve encircling said neck, a key for restraining movement between said valve member and sleeve, a handle secured to said sleeve for rotating said valve member, a motor carried by said sleeve and having a shaft extending through said sleeve, neck and into said chamber, and an agitator carried by said shaft and disposed within said chamber.

7. In a dispensing device for liquids, a valve body having a vertical bore open at the top and bottom, a spout secured to the lower end of said valve body and providing a discharge outlet, said valve body having a valve inlet intermediate the upper and lower ends thereof, a cup-shaped valve member disposed within said bore and having a closed bottom, said valve member being formed with a chamber within the same, said valve member having a passageway therein for bringing said inlet into communication with the lowermost portion of said chamber, said valve member having another passageway therein for bringing the upper portion of said chamber into communication with said outlet, and an agitator within said chamber.

8. In a dispensing device for liquids, a valve body having a bore therein and provided with a discharge outlet and an inlet, a cup-shaped valve member disposed within said bore and formed with a chamber, said valve member having a passageway communicating with said chamber at the lowermost portion thereof and with said inlet and having another passageway communicating with said chamber at a higher elevation and with said outlet, said valve member upon 10 rotation to one of its positions closing said inlet, and an agitator within said chamber.

9. In a dispensing device for liquids, a valve body having a bore therein and provided with a discharge outlet and an inlet, a cup-shaped valve member disposed within said bore and formed with a chamber, said valve member having a passageway communicating with said chamber at the lowermost portion thereof and with said inlet and having another passageway communicating with said chamber at a higher elevation and with said outlet, said valve member upon 15 rotation to one of its positions closing said inlet, said valve body having a passageway connected with the first named passageway of said valve member and communicating with the discharge outlet of said valve body when the valve member is in said denoted position and agitating means within said chamber.

10. In a dispensing device for liquids, a valve body having a vertical bore and provided with a discharge outlet at the lower end and with a port extending through said bore near the upper end thereof and forming an inlet, a cup-shaped valve member disposed within said bore and 30

formed with a chamber within the same, said valve member having a port extending through the bottom thereof and a passageway communicating therewith and adapted to register with the port of said inlet, said valve member having another port near the upper portion thereof and substantially at the elevation of the port of the inlet, and a passageway communicating with said last named port and with said outlet, and an agitator within said chamber.

11. In a dispensing device for liquids, a valve body having a vertical bore and provided with a discharge outlet at the lower end and with a port extending through said bore near the upper end thereof and forming an inlet, a cup-shaped valve member disposed within said bore and formed with a chamber within the same, said valve member having a port extending through the bottom thereof and a passageway communicating therewith and adapted to register with the port of said inlet, said valve member having another port near the upper portion thereof and substantially at the elevation of the port of the inlet, and a passageway communicating with said last named port and with said outlet, and an agitator within said chamber, said valve member upon rotation to one of its positions closing the port of said inlet and said valve body having another passageway communicating with said outlet and adapted to communicate with the first named passageway in said valve body when the valve member is in closing position.
